OSSIAN E. DODGE, OF ST. PAUL, MINNESOTA.

Letters Patent No. 84,270, dated November 24, 1868.

IMPROVEMENT IN REFLECTORS FOR PUBLIC HALLS, &c.

The Schedule referred to in these Letters Patent and making part of the same.

To all whom it may concern:

Be it known that I, OSSIAN E. DODGE, of St. Paul, in the county of Ramsey, and State of Minnesota, have invented certain new and useful Improvements in Head-Light for Public Halls, &c.; and I do hereby declare that the following is a full and complete description of the same, reference being had to the accompanying drawings, making a part of this specification, in which—

Figure 1 is a front view of the light.

Figure 2, a side view.

Like letters of reference refer to like parts in the several views.

The nature of this invention relates to a head-light for public halls, theatres, &c., where the light may be required to be reflected from one part of the house to another, or excluded from one place and concentrated in another, for scenic or dramatic effect.

In fig. 1, A represents a section of gas-pipe, in which is a series of burners or nipples, B, more or less in number, as may be required. This pipe is arranged at right angles to the supply-pipe C, leading from the meter. Above and in the rear of this pipe is a rod, D, to which is attached loosely a double reflector, E, by means of the rings F, whereby it can be raised upward, or lowered from or over the burners, as and for a purpose hereinafter shown.

The practical operation of this arrangement is as follows, viz:

This head-light is hung up at an angle of about forty-five degrees from the front of the stage. In this relation to the stage the best effect is obtained.

The position of the reflector, in its relation to the burners, as shown in fig. 2, is such that the light will be reflected from two plane surfaces, E and G, as indicated

by the dotted lines a, which diffuse the light widely over the hall or stage.

Now, should it be required to throw the light upon any one part of the room, or upon the stage only, the reflector is lowered by means of the cord H, which, for convenience, may be carried to the ante-room, or to some other convenient place.

It will be obvious that on lowering the reflector, the rays of light may be thrown at any angle required, thereby concentrating them, by the double reflector, in a most brilliant manner upon any one place desired.

This adjustment of the reflector, by means of the cords, unseen by the audience, places the light for scenic and dramatic purposes immediately under the command of the scene-manager, so that he can regulate the light without in any way attracting the attention of the people, or causing the least delay in the progress of the performance.

This augmentation of the light, by the double character of the reflector, saves largely in the expense of lighting the house; hence, this head-light is not only valuable for its convenience in changing the direction of the light, but also in view of the saving in the consumption of gas.

What I claim as my invention, and desire to secure by Letters Patent, is—

The double reflector E, as arranged and operated by the cord H, in combination with the pipe A and burners, for the purpose specified.

OSSIAN E. DODGE.
